UNITED STATES PATENT OFFICE.

THOMAS B. JEFFERY, OF KENOSHA, WISCONSIN.

STARTING DEVICE FOR EXPLOSIVE-MOTORS.

No. 826,252.

Specification of Letters Patent.

Patented July 17, 1906.

Application filed June 10, 1901. Serial No. 63,847.

To all whom it may concern:

Be it known that I, THOMAS B. JEFFERY, a citizen of the United States, residing at Kenosha, in the county of Kenosha and State of Wisconsin, have invented certain new and useful Improvements in Starting Devices for Explosive-Motors, of which the following is a specification, reference being had to the accompanying drawings, forming a part thereof.

10 The purpose of this invention is to provide means for insuring that at the time of starting an explosive-motor the igniter shall be so adjusted that the first explosion shall occur at proper stage to produce forward and not reversed motion.

15 It consists of the features and details of construction set out in the claims.

In the drawings, Figure 1 is a vertical section transversely with respect to a fore-and-aft main crank-shaft of the motor of a vehicle having such motor provided with my invention. Fig. 2 is a section at the line 2 2 on Fig. 1. Fig. 3 is a detail, partly sectional, in the vertical plane of the axis of the engine 25 crank-shaft, showing a modified form of my invention. Fig. 4 is a detail elevation similar to Fig. 2, but not including the main crank-shaft, showing a further modification of my invention.

30 In the drawings I have shown my invention applied to the motor of a vehicle in which the main crank-shaft of the motor extends longitudinally fore and aft with respect to the vehicle. It will be obvious to any one 35 skilled in the art that slight changes, which any mechanic will readily make, will adapt it to a vehicle in which the main crank-shaft extends transversely.

40 A represents the main crank-shaft of the motor; B, a counter-shaft in convenient position to be rotated by a proper crank-handle and deriving motion from the main crank-shaft by means of the chain c, passing around the sprocket-wheels a and b on the two 45 shafts, respectively. I have shown the counter-shaft B extending through and journaled in a board D, which may be called the "controller-supporting" board, on which there is mounted the controller E for an electric igniter. This element is of the form which is 50 fully shown and described in my application, Serial No. 3,956, filed February 5, 1900, and need not be further described herein except to say that the lever-arm E' extends from a 55 plate e', which is adjustable by means of said lever-arm about the axis of the device to

change the time of sparking with respect to the piston's movement, rotation in the direction of the arrow on Fig. 2 having the effect to cause the sparking to occur in the piston's 60 retreating stroke and movement in the opposite direction has the effect to retard or delay the sparking.

F is a lever-arm mounted on the board D and connected by the link G to the adjusting-arm E' of the igniter-controller. A spring f is provided operating upon the lever-arm F, tending to hold it in the position shown in Fig. 2, at which the pin g, by means of which the link G engages and actuates the arm E', 70 is in position to allow the arm E' its full range of adjusting movement in both directions.

On the counter-shaft B are clutch-teeth B² B², adapted to be engaged by the hub H' of the handle H, which is provided for the use of the operator in starting the motor by hand, said hub having proper form for engagement with such clutch to rotate it in the proper direction for starting the motor, but 80 adapted to be forced out of engagement by the incline of the engaging clutch-teeth when the motor is driven faster than the handle is being turned, the mode of use, as well understood, being to operate the motor by hand by 85 means of the handle through one cycle in order to initiate the proper action, which will be continued automatically by the explosion at proper time in the next and succeeding cycles, the handle being withdrawn from engagement as soon as the automatic action of 90 the motor commences. The hub of the handle H is tapered, widening back from the clutch end of the hub, constituting a cam H¹⁰, adapted to act against the side of the 95 lever F to crowd the latter away from the shaft when the handle is forced into engagement for operating the shaft. The movement given to the lever F by this action is sufficient to cause the link G, by means of the 100 pin g thereon, to move the adjusting-arm E' of the igniter-controller to the position shown in dotted line in Fig. 2, which is the position at which ignition is delayed, so as not to occur until after the piston has started back in 105 its retreat after its compressing stroke, so that an explosion occurring at that time is certain not to produce rotation in reversed direction. As soon as the action of the 110 engine is commenced and the handle is forced out of engagement or is voluntarily removed by the operator, the spring f returns the le-

ver F to its original position, carrying the ping on the link G out of the way of the adjusting-arm E' of the igniter-controller, leaving that arm free to move to any position within its range of adjustment obedient to any means which may be provided for effecting such adjustment automatically or at will. Such means are not herein shown, no specific means for that purpose being essential to the present invention.

In Fig. 3 I have shown a modification of this device. In this form I have shown the operating-handle arranged to be applied directly to the engine crank-shaft instead of to a counter-shaft, and the lever F', by which the adjusting-arm of the igniter-controller is operated, is pivoted so as to swing in a plane radial to the shaft instead of transversely thereto, as in the principal form shown, said lever having an aperture F¹⁰, through which the crank-shaft extends and outside of which said shaft is adapted to receive the operating-handle. In this form the igniter-controller is mounted on a horizontal support instead of upon the vertical board, as in the other form, and the end of the lever F' extends up past the finger E' of said controller and is arranged to force said finger to the position for delayed ignition when the handle applied to the end of the main crank-shaft collides with the lever and forces it back on the shaft in order to admit the handle. A spring f is provided, as in the other construction, to hold the lever F' normally in position at which it will not obstruct the adjusting movement of the finger E'.

A further modification may be understood from Fig. 4, in which the lever F², operating in the same manner as the lever F in Fig. 2 in the first form, so far as its action upon the adjusting-finger of the igniter-controller is concerned, operates to entirely obstruct the end of the counter-shaft, so as to prevent the handle from obtaining access to the shaft until said lever has been swung out of obstructing position by the operator. The difference between this form and the other two is merely that the movement of the lever out of position at which it prevents engagement of the handle with the shaft is not automatic, as in the first two forms. I consider the automatic form of device somewhat preferable, and of the three forms that first described has a slight additional advantage over the others, in that it permits the lever F to be utilized as a key to hold the handle in engaged position on the shaft until it is either withdrawn voluntarily by the operator or forced out of engagement by the more rapid rotation of the shaft, said expedient consisting in providing a groove H² on the hub of the handle, into which the edge of the lever is adapted to take when the handle is forced into engagement. The side of the groove 65 and the corresponding portions of the proper

edge of the lever are beveled, so that the engagement will not prevent the withdrawal of the handle by the operator or its disengagement from the shaft by the automatic action of the clutch.

It will be evident that this invention is not limited to use with a crank for a starting-handle nor to use with a hand-operated starting-lever, and by the word "handle," applied to the crank shown in the principal figures, I do not limit them to exclude any form of lever which may be moved by the operator or motorman for starting the engine; nor by the term "lever" do I intend to exclude a wheel such as shown in dotted line 80 in Fig. 1, (marked H^a), which may be substituted for the crank-handle. In Fig. 5 I have shown a form of handle h for starting which may at all times remain on the shaft, but which is forced out of operative engagement 85 therewith by rotation of the shaft after the automatic action commences, the engaging stud a' acting on the spiral incline h' of the hub of the wheel and forcing the latter longitudinally on the shaft until the stud clears 90 the engaging shoulder h² and thereafter revolves without encountering or actuating the handle. In this form I have also shown the lever F actuated not by the movement of the handle, which effects operative engagement 95 of the latter with the shaft, but by the rotary movement of the handle while engaged, the cam protrusion h³ on the hub of the hand-wheel being located at such part of the circumference relatively to the engaging shoulder h² as to commence to force the lever out and adjust the igniter-controller to position for delayed ignition and at proper time in the first revolution to forestall ignition.

I claim—

1. The combination with a shaft of an explosive-engine by whose rotation the engine may be started and an electric circuit-breaker mounted apart from said shaft and movable for varying the time of ignition, and a sparking device connected with said circuit-breaker of a movable guard for the shaft which at normal position obstructs the operative engagement therewith of a turning device, and connections from said guard to the movable 115 electric circuit-breaker.

2. The combination with a shaft of an explosive-engine by whose rotation the engine may be started and an electric circuit-breaker mounted apart from said shaft and movable 120 to vary the time of ignition, and a sparking device connected with said circuit-breaker, of a movable guard for said shaft, means for holding it normally in position to obstruct the movement of a turning device to operative position for turning the shaft, and connections from said movable guard to said movable electric circuit-breaker, the relative position and connections of said two connected movable elements being such that the move- 130

ment of the guard out of obstructing position adjusts the circuit-breaker for affecting the time of ignition.

3. The combination with a shaft of an explosive-engine by whose rotation the engine may be started and an electric circuit-breaker mounted apart from said shaft and movable to vary the time of ignition and a sparking device connected with said circuit-breaker, 5 of a movable guard for said shaft; means for holding the guard normally in position to obstruct the operative engagement of a turning device with the shaft, and adapted to be forced by the latter out of such obstructing 10 position in the introduction of the turning device to such operative position, and connections from said movable guard to said movable circuit-breaker.

4. The combination with a shaft of an explosive-engine and an electric circuit-breaker, 20 movable to vary the time of ignition, and a sparking device connected with the latter, of a guard arranged to move transversely of the shaft and stopped laterally near the same; 25 means for holding it yieldingly in such stopped position, said guard being adapted to be crowded laterally away from the shaft by the engagement of a turning device with the latter, and connections from said guard 30 to said movable circuit-breaker for adjusting the latter by the movement of the former from obstructing position.

5. In an explosive-motor, in combination with a shaft by whose rotation the motor may 35 be started; a device mounted apart from said shaft, for controlling the time of ignition in the cycle of the engine's action; means for rotating the starting-shaft; a lever and connections by which it moves said controlling de- 40 vice to vary the time of ignition, said lever extending in proximity to the starting-shaft in position to be encountered and moved by the means for rotating the shaft in the movement of said means toward position of opera- 45 tive engagement with the shaft.

6. In an explosive-motor, in combination with a shaft by whose rotation the motor may be started; a device mounted apart from said shaft for controlling the time of ignition 50 in the cycle of the motor's action; a handle for rotating said shaft; a lever and connections by which it moves said controlling device to vary the time of ignition, said lever extending in position obstructing the operative engagement of the handle with the shaft, and arranged to adjust the controller for affecting the time of ignition by movement out of such obstructive position.

7. In an explosive-motor in combination 55 with a shaft by whose rotation the motor may be started; a device mounted apart from said shaft for controlling the time of ignition in the cycle of the motor's action; a handle for rotating said shaft; a lever and connections by which it moves said controlling de-

vice to vary the time of ignition, said lever extending in proximity to the starting-shaft, and at all points corresponding to advanced ignition obstructing the engagement of the handle with the shaft; said lever being movable at will from such obstructing position to position corresponding to delayed ignition. 70

8. In an explosive-motor, in combination with a shaft by which the motor may be started; a device mounted apart from said shaft, which controls the time of ignition in the cycle of the motor's action; a handle for operating such shaft; a lever and connections by which it moves the controlling device to vary the time of ignition, said lever extending in proximity to the starting-shaft, and adapted to stand in position obstructing the operative engagement of the handle with the shaft, said lever and handle being relatively constructed so that the latter forces the former out of obstructing position in coming into engagement with the shaft, the lever being arranged and connected so that such forced movement of the latter adjusts the controller for affecting the time of ignition. 80

9. In an explosive-motor, in combination with a controller for the igniter, adjustable to vary the time of ignition in the cycle of the engine's movement, a shaft by whose rotation the engine may be started; a handle for operating such shaft; an element arranged to move transversely of the shaft, and laterally stopped near the same; the handle being adapted to crowd such element laterally 90 away from the shaft as said handle is engaged with the latter; and connections by which such movement of said element away from the shaft operates the adjusting means of the igniter-controller to set the latter at position for affecting the time of ignition. 100

10. In an explosive-motor, in combination with the controller for the igniter, adjustable to vary the time of ignition in the cycle of the engine's movement, a shaft by whose rotation the engine may be started; an element 110 arranged to move transversely of the shaft and stopped near the same; and means tending to hold it yieldingly toward the shaft, said element being located in the path of the starting-handle so as to be crowded away 115 from the shaft as said handle is engaged by the latter; and connections from said element to the means for adjusting the igniter-controller, by which such movement away from the shaft sets the controller in position for affecting the time of ignition; the handle having a shoulder back of which said element becomes engaged when the handle is engaged with the shaft, whereby such shoulder tends to resist disengagement of the handle. 120

11. In an explosive-motor, in combination with a controller for the igniter, adjustable to vary the time of ignition in the cycle of the engine's movement, a shaft by whose rotation the engine may be started; a handle for 130

- operating such shaft having its hub which passes onto the shaft adapted to engage the latter only when rotating in one direction; a lever pivoted so as to swing transversely of the shaft, and a spring tending to hold it theretoward, whereby the lever is located in the path of the starting-handle so as to be crowded away from the shaft by the application of the handle thereto; means by which the lever engages the handle to retain it on the shaft; and connections from the lever by which this movement away from the shaft adjusts the igniter-controller to position affecting the time of ignition.
12. In an explosive-motor, in combination with a controller for the igniter, adjustable to vary the time of ignition in the cycle of the engine's movement, a shaft by whose rotation the engine may be started; a handle for operating such shaft, having its hub which passes onto the shaft adapted to engage the latter only when rotating in one direction; a lever pivoted so as to swing transversely of the shaft and a spring tending to hold it theretoward; the handle and said lever being relatively formed so that the introduction of the handle to position of engagement with the shaft crowds the lever away from the latter, and the handle having a groove with which the lever is adapted to be engaged when the handle is engaged with the shaft, whereby said lever serves to retain the handle in such engagement, and connections from the lever by which its movement away from the shaft adjusts the igniter-controller to position affecting the time of ignition.
13. In an explosive-motor, a handle or starting-lever comprising a hub adapted to be passed onto the starting-shaft and to engage the latter by rotation in one direction, said hub having an annular groove adapted to be engaged by a retaining device to resist its withdrawal from the position at which it engages the shaft.
14. In an explosive-motor, a handle or starting-lever having a hub adapted to be passed onto the starting-shaft and provided at the end with ratchet-teeth for engaging the shaft for rotation in one direction, and a peripheral groove back of the ratchet-teeth for engagement of a retaining device, the ratchet-toothed end of the hub being conically tapered, widening from the points of the teeth back toward the groove to adapt it to enter past such retaining device.
15. In an explosive-motor, in combination with a shaft by whose rotation the motor may be started, a device mounted apart from said shaft for controlling the time of ignition in the cycle of the engine's action; a lever and connections by which it moves said controlling device to vary the time of ignition, said lever extending in proximity to the starting-shaft in position to be encountered and moved by means for rotating the shaft in the movement of said means toward position of operative engagement with the shaft.
16. In an explosive-motor, in combination with a shaft by whose rotation the motor may be started; a device apart from said shaft for controlling the time of ignition in the cycle of the motor's action; a lever and connections by which it moves such controlling device to vary the time of ignition, said lever extending in a position obstructing the operative engagement of the starting-handle, and arranged to adjust the controller for affecting the time of ignition by movement out of such obstructive position.
17. In an explosive-motor, in combination with a shaft by whose rotation the motor may be started, a device apart from said shaft for controlling the time of ignition in the cycle of the motor's action; a lever and connections by which it moves said controlling device to vary the time of ignition, said lever extending in proximity to the starting-shaft, and at all points corresponding to advanced ignition obstructing the engagement of the starting-handle with the shaft, said lever being movable at will from such obstructing position to position corresponding to delayed ignition.
18. In an explosive-motor, in combination with a shaft by which the motor may be started, a device apart from such shaft which controls the time of ignition in the cycle of the motor's action; a lever and connections by which it moves the controlling device to vary the time of ignition; said lever extending in proximity to the starting-shaft and adapted to stand in position obstructing the operative engagement of the starting-handle, and adapted to be forced by the latter out of obstructing position, the lever being arranged and connected so that such forced movement adjusts the controller for affecting the time of ignition.
19. In an explosive-motor, in combination with a controller for the igniter adjustable to vary the time of ignition in the cycle of the motor's movement, a shaft by whose rotation the motor may be started; an element arranged to move transversely of the shaft, and laterally stopped near the same, and adapted to be crowded laterally away from the shaft by the engagement of the starting-handle with the latter, and connections by which such movement of said element away from the shaft operates the adjusting means of the igniter-controller to set the latter at position for affecting the time of ignition.
- In testimony whereof I have hereunto set my hand, at Kenosha, Wisconsin, in the presence of two witnesses, this 5th day of June, A. D. 1901.
